BLANKET HOLDER

John Straka, Chicago, Ill.

Application November 17, 1949, Serial No. 127,966

1 Claim. (Cl. 24—72.5)

My invention relates to a novel adjustable clamping device for releasably securing fabrics and the like and more particularly my device relates to a clamp which is especially adapted to releasably and adjustably retain blankets or bed covers in position on a bed.

To my knowledge until the invention of my novel clamp no satisfactory method for securing blankets and the like in the desired position on a bed has been known.

The device which I have invented although primarily intended for use upon beds which are occupied by children, invalids and restless people may easily and obviously be utilized in other manners and it should be understood that I do not intend to be limited to the use of my novel device to use for securing blankets and bed clothing. It is an object of my device to provide an adjustable fabric clamping device which may be adjusted to clamp the various thicknesses of fabrics without distorting the device and without tearing the fabric units which are secured or held.

Other and further objects of my invention will become apparent from the following description and appended claim, reference being had to the accompanying drawings and numerals of reference thereon.

On the drawings:

Fig. 1 is a side elevation of my novel clamping device and taken on a plane of the line 1—1 in Fig. 3, looking in the direction of the arrows.

Fig. 2 is a vertical sectional view taken on the plane indicated by the line 2—2 of Fig. 1 and looking in the direction of the arrows.

Fig. 3 is a front elevational view of my novel device.

Fig. 4 is a side elevational view of my device taken on the same plane as the view of Fig. 1 and illustrating the position of the elements when my novel device is in open and non-clamping positions.

Fig. 5 is a fragmentary view of a bed and illustrating one manner of use of my novel device.

Fig. 6 is a modified form of my invention and illustrating the use of the clamping device without a cam.

Referring to Fig. 5, it will be seen that one manner of use of my device is illustrated and numeral 10 designates a bed end including a pair of legs 11 and a connecting tie or rail 12 and including a plurality of vertically disposed horizontally spaced slats or supporting elements 13 which connect the tie 12 and the upper portion of the connected together legs 11. Numerals 14

5 designate the usual pair of bed rails which are illustrated as being connected at one end to the legs 11. Numeral 15 designates a pair of transversely extending supports which are supported by the rail 14 and which in turn support a mattress or the like 16. Numeral 17 which is illustrated in Figs. 1 and 5 designates a plurality of blankets or fabric units which are retained by my novel device to be hereinafter described as 10 illustrated.

2 To anchor my device to the bed frame a suitable anchor or connecting tie or loop 18 which may be of a fabric or elastic construction is suitably retained on portions of the bed frame such as rails 14 and the vertical ties 13, as illustrated in Fig. 5. The upper end of the cord or tie 18 is looped through a portion of my novel device as illustrated in Figs. 1 and 4 and at 18a in Fig. 6.

20 More particularly with reference to my novel clamp, numeral 19 designates an angularly bent yoke which may be of metal wire or other suitable construction. The yoke 19 includes an intermediate substantially V-shaped portion comprising a pair of outwardly extending legs 20 and 21. An integral and upper portion 22 of the leg 21 extends inwardly as illustrated in Figs. 1 and 4 and as illustrated in Figs. 2 and 3 said portion 22 is preferably of square or rectangular cross-section to retain the sleeve or bushing 23, to be hereinafter described, from undesirable rotation. It will be understood, however, that I do not limit my invention to the particular shape of the extension 22 as equivalent means may be utilized to retain the sleeve or bushing 23 from undesirable movement.

35 The bushing or sleeve 23, previously designated, in one form of my invention has an enlarged partially enclosed chamber 24 and has external threads 25. The sleeve or bushing 23 has an outwardly extending end flange or lip designated as 26, and has an inwardly extending flange 29 which defines a square hole or opening through which the extension 22 extends as illustrated in Fig. 2.

40 As illustrated in Figs. 1 and 4, adjustably and threadingly mounted on the sleeve or bushings 23 is a ball, pressure head or block 27 which is internally threaded as indicated at 28. The pressure block or head 27 cooperates with an integral eyelet or socket ring 30 which is integral with and carried by an upper portion of the angularly extending leg 20 to releasably retain fabric units or blankets designated as 17. It will be understood that I can adjust the space between the end

of the head 27 and the ring or eyelet 30 by appropriately threading head 27 inwardly or outwardly to accommodate various thicknesses of fabric.

The longitudinal dimension of the head or block 27 is greater than the distance between the end of the head 27 and the ring 30. In the assembling of my device the original shape of the yoke 19 is as illustrated in the dotted lines in Fig. 4 so that the head 27 and other elements to be hereinafter described may be assembled. After assembly of head or block 27 and said other elements to be hereinafter described, the yoke 19 is preferably placed in a die and forced into the permanent position illustrated in solid lines in Fig. 4. As illustrated in Figs. 1, 3 and 4, a cam having an integral handle or shank portion 31 comprising a pair of side flanges 32 is pivoted to the angularly bent leg 19 by means of a pair of bosses or lugs 33 which are integral with respective flanges 32 and which extend inwardly in aligned positions into the curved recess formed by the juncture of the arm 22 and the leg 21. The upper portion 34 of the handle 31 is formed with cam faces 35 which adjustably engage the flanges 26 and 29 of the sleeve 23 to cause said sleeve to move inwardly or outwardly as the handle 31 is appropriately moved. It will be appreciated, of course, that in place of lugs or bosses 33 a suitable pivot pin or its equivalent may be employed.

In order to retain the cam lugs 33 of the operating lever handle 31 in adjusted positions, I mount a compression spring 36 around the guide extension 22 as illustrated in Figs. 1 and 4, said spring at one end being in abutment with the inner surface of the flange 29 and the other end being in abutment with a washer 37 or the like which I secure in position on one end of extension 22 by flattening the end of said extension 22 as illustrated at 38 in Figs. 1 and 4. Additionally, the cam is preferably retained in its position on the yoke 19 independently of any pressure exerted by sleeve 23. Such retention results from the limitation of longitudinal movement of pivot 33 by the curvature of the upper portion of arm 21. It will be seen therefore that as I move the lever handle 31 to the position illustrated in Fig. 1, the sleeve or bushing 23 carrying the adjustable pressure head 27 will be slid inwardly to impinge the fabric units 17 between the ring 30 and the head 27, and as I move the lever handle to the position illustrated in Fig. 4, the sleeve or bushing 23 will be carried outwardly by virtue of the action of spring 36 to release retained fabric elements or the like. To keep the cam faces 35 from spreading, the end portion of flange 26 is preferably flat, as illustrated in Figs. 1 and 2 so that said faces will uniformly engage flange 26.

As illustrated in Fig. 6, a modified form of my invention may be used when optionally desired, said modified form being operable without a cam. In the form illustrated in Fig. 6, the elements include the connector 18a, yoke 19a, extension 22a,

bushing 23a, head 27a, and ring 30a and are substantially similar to corresponding elements designated in the main form of the device hereinabove described. It will be noted, however, that the bushing or sleeve 23a is press-fit on the square extension 22a so that said bushing or sleeve 23a will not rotate or move longitudinally. In this modified form of the invention I rely solely upon the adjustment of the internally threaded head 27a with respect to the externally threaded sleeve 23a to impinge or release the fabrics retained between the head 27a and the ring 30a.

As many changes could be made in the above construction, and as many apparently widely different embodiments of my invention, within the scope of the claims could be constructed without departing from the spirit and scope thereof, it is intended that all matter contained in the accompanying specification shall be interpreted as illustrative and not in a limiting sense.

I claim:

In a clamping device for sheet material, a stiff wire yoke comprising a pair of integral legs disposed angularly with respect to each other, one leg having a wire ring at its outer end, the other leg having at its outer end an extension projecting toward and co-axial with and spaced from said ring, a cup-like member telescoped about said extension, with the rim of said member between said ring and the base of said member, a spring confined between said base and the inner end of said extension and biasing said member away from said ring, a head threaded to and about said member and having a rounded end between said extension and said ring, and releasable means engageable with said base for moving said member toward said ring against the resistance of said spring to bring said rounded end into proximity to said ring to thereby pinch sheet material peripherally in the annular space between said rounded end and said ring, said means being cooperative with said base to releasably retain said rounded end in pinching position.

JOHN STRAKA.
